Attorney.

UNITED STATES PATENT OFFICE.

GEORGE W. NORDSTROM, OF BROOKLYN, NEW YORK.

RAISING AND LOWERING DEVICE FOR HATCH-VENTILATORS.

1,385,574.

Specification of Letters Patent. Patented July 26, 1921.

Application filed August 27, 1920. Serial No. 406,376.

To all whom it may concern:

Be it known that I, GEORGE W. NORDSTROM, a citizen of the United States, and resident of 69 Seventy-fifth St., Brooklyn, in the county of Kings and State of New York, have invented certain new and useful Improvements in Raising and Lowering Devices for Hatch-Ventilators, of which the following is a specification.

10 My invention relates to raising and lowering devices for hatch covers and has for its object to provide a simple and effective means for the purpose set forth. I accomplish this by means of the mechanism illustrated in the accompanying drawings in which:

Figure 1 is a vertical longitudinal sectional view through a hatch coaming and hatch cover, with the raising and lowering device attached and showing the hatch cover in closed position.

Fig. 2 is a view similar to Fig. 1 but showing the hatch cover held in open position;

25 Fig. 3 is a vertical transverse sectional view through Fig. 1; and

Fig. 4 is a vertical transverse sectional view through Fig. 2.

Referring more particularly to the drawings 30 5 denotes the hatch coaming of a ship and 6 the hatch cover connected to the coaming as by hinges 7.

At the present time the covers 6 used on oil carrying ships are very heavy and in consequence are very generally lifted for 35 ventilating purposes by means of an extensive angle iron frame and block and tackle connections requiring many men to operate and when lifted and raised the cover is propped open by a bar or the like. Many 40 accidents have been caused by men sent to close the hatch covers, removing the prop bar suddenly and letting the cover drop, this sudden closing of the hatch often causing 45 an explosion.

The present opening and closing device for the hatch cover 6 comprises a shaft 8 suitably mounted in bearings 9 and 10 on the inside of the hatch coaming, one end 11 of the shaft being squared and extending through the coaming for turning by means of a wrench or other tool. Right and left hand threaded portions 12 and 13 respectively are formed on the shaft upon which

are mounted correspondingly threaded nuts 14 and 15. Pairs of lower crossed bars 16 and 17 of a "lazy tongs" 30 are pivotally connected to opposite sides of the nuts 14 and 15 respectively by means of pins or the like 18 and 19, while pairs of upper bars 20 and 21 of the lazy tongs are connected to opposite sides of swivel blocks 22 and 23 respectively as by means of pins 24 and 25, the block 22 being connected to the lug 22' on the hatch cover in any suitable manner, as by means of a pin 35. Suitable spacing blocks 40 between the bars of each pair serve to brace and maintain the bars in fixed spaced relation to each other.

From the foregoing the operation of the 70 invention will be apparent but may be briefly described as follows: When the operator desires to open the hatch cover he turns the shaft 8 by means of the squared end 11, thus causing the nuts 14 and 15 to 75 travel toward each other on the threaded portions 12 and 13 until the "lazy tongs" have been straightened out to Fig. 2 position. The closing of the hatch can of course be effected by rotating the shaft in a reverse direction. While I have found in actual practice that the hatch cover will remain in any adjusted position the pawl and ratchet mechanism 26 on the hatch coaming serves to lock the cover in open position. 80 The set screw 27 on the shaft bearing 9 might also be utilized for this purpose.

Having thus described my invention, what I claim is:

In combination with a hatch coaming having a pivoted hatch cover, a shaft rotatably mounted in bearings on the inside of said coaming, said shaft having a squared end extending through the wall of said coaming, oppositely threaded portions on said shaft, 90 correspondingly threaded nuts on said threaded portions, swivel blocks connected to the inside of said cover, pairs of cross bars pivotally connected to opposite sides of said nuts, and pairs of bars connected to opposite sides of said swivel blocks and to the upper ends of said first mentioned bars, and spacing bushings arranged between the bars of each pair, substantially as described.

Signed at New York city, in the county 105 of New York and State of New York, this third day of August A. D. 1920.

GEORGE W. NORDSTROM.
